RAILWAY TRACK CIRCUIT APPARATUS

Filed June 18, 1930

INVENTOR:

B. E. O'Hagan,

BY C. S. S. - 19

U. S. Senate

UNITED STATES PATENT OFFICE

BERNARD E. O'HAGAN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRACK CIRCUIT APPARATUS

Application filed June 18, 1930. Serial No. 461,952.

My invention relates to railway track circuit apparatus, and particularly to apparatus of the type involving a main track circuit, one of the rails of which is divided to form 5 an auxiliary track circuit. One object of my invention is the provision of means, in apparatus of this character, for preventing bobbing of the track relay for the auxiliary track circuit when a car alternately bridges and 10 shunts the auxiliary track circuit.

I will describe one form of apparatus embodying my invention, and will then point out the novel features thereof in claims.

The accompanying drawing is a diagrammatic view showing one form of apparatus embodying my invention.

Referring to the drawing, the reference character A designates a railway track, the rails 1 and 1^a of which are divided by insulated joints 2 to form a main track section C—D. This section is provided with the usual track circuit comprising a source of current E connected across the rails at one end of the section, and a main track relay R connected across the rails at the other end of the section. The source of current E, as here shown, is a transformer, the secondary of which is connected with the track rails and the primary of which is connected with a 20 source of alternating current which is not illustrated in the drawing.

The track rail 1^a is further divided by insulated joints 2^a to form a short insulated section 3, and the main track circuit current is 25 conducted around this section by a wire 6. The section 3 is provided with an auxiliary track circuit comprising a transformer E^x and an auxiliary track relay R^x. One terminal of the secondary of transformer E^x is 30 connected with the rail 1 and the other terminal is connected with insulated section 3 of rail 1^a. Similarly, one terminal of track relay R^x is connected with rail 1 and the other terminal is connected with insulated 35 section 3 of rail 1^a.

It will be seen from the foregoing that each track relay is normally energized, that track relay R will become deenergized when a train enters section C—D, but that track relay R^x will not become deenergized until a por-

tion of the train enters insulated rail section 3.

With the apparatus thus far described, if a car having a wheel base longer than the length of insulated rail section 3 should pass over this section, relay R^x would become energized when the car bridges the section. In order to avoid this contingency, I have provided a shunt around one of the insulated joints 2^a, which shunt includes a back contact 4 of relay R^x and an adjustable resistance 5.

Assuming now that a car which is long enough to bridge the entire length of section 3 passes over the track, when the first truck of this car enters section 3, it will deenergize relay R^x, but when the car bridges section 3, so that no wheel lies within this section, relay R^x will remain deenergized because of a shunt path which passes from the left hand terminal of relay R^x, through back contact 4, resistance 5, the wheels and axles of the car, and rail 1 to the right-hand terminal of relay R^x.

When a car moving toward the right enters the short section 3, it will immediately deenergize relay R^x, and after this car has passed a certain distance beyond section 3 the voltage across the terminals of relay R^x will rise to such value that this relay will again pick up. The point at which this will occur, can be varied by adjusting the resistance 5.

Apparatus embodying my invention is particularly well adapted for use in connection with the control of highway crossing signals, and may, for example, be used in systems such as those disclosed and claimed in application for Letters Patent of the United States, filed by G. W. Baughman on July 17, 1930, Serial No. 468,538.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a main section of railway track having one rail divided by insulated joints to form a short auxiliary section, a track circuit for said main section including a source of current connected across the rails at one end of the section and a main track relay connected across the rail at the other end of the section, a track circuit for said auxiliary section including a source of current and an auxiliary track relay, and a shunt around one of said insulated joints including the back contact of the auxiliary track relay.
2. In combination, a main section of railway track having one rail divided by insulated joints to form a short auxiliary section, a track circuit for said main section including a source of current connected across the rails at one end of the section and a main track relay connected across the rail at the other end of the section, a track circuit for said auxiliary section including a source of current and an auxiliary track relay, and a shunt around one of said insulated joints including the back contact of said auxiliary track relay and an adjustable resistance.

In testimony whereof I affix my signature.
BERNARD E. O'HAGAN.
